[57] ABSTRACT

A shoulder strap bag formed from a tube of thin flexible material, having a seam across the bottom, and an inverted U-shaped cut above the bag forming the remainder of the material into a shoulder strap and two flaps which may be hung from the upper edges of the bag, one flap folded over the top opening of the bag and hanging outside the upper flap.

SHOULDER STRAP BAG

FIELD OF THE INVENTION

This invention relates to shoulder strap bags.

BACKGROUND OF THE INVENTION

Shoulder strap bags have recently been popularized. It is my purpose to provide a novel, very inexpensive, shoulder strap bag, in contrast to those smart and relatively expensive bags made of leather, and provided with a leather shoulder strap loop, such as are now used as a fashion accessory by both men and women. In other words, it is my purpose to provide a novel, very inexpensive, utility shoulder strap bag, of very great all around usage, for example, as a shopping bag or the like, or a bag in which an article such as a dress may be packaged by a store for convenient carriage home by the purchaser.

BRIEF DESCRIPTION OF THE INVENTION

The article of the invention is made from thin, flexible, plastics material. This material is made in a tube preferably about 27 $\frac{3}{4}$ inches long, and with a circumference of about 31 $\frac{1}{2}$ inches. This tube, in a flattened condition, is formed with a weld seam at the bottom, forming the bottom of the bag, and is preferably formed with rounded corners at the top. With the tube flat, a cut is then made in an inverted U form, beginning at a point about 12 inches up from the bottom of the bag, and spaced about 1 $\frac{1}{4}$ inches inwardly from one side edge of the flattened tube, the cut extending vertically upward from this point, around the upper end rounded corner, still at 1 $\frac{1}{4}$ inches inside the outer boundary of the article, horizontally across, around the inside of the opposite upper end rounded corner, and vertically downward to a point located like the beginning point but adjacent the opposite edge of the bag. Two flaps or aprons are thereby formed, and these may be folded down on a line joining the two points mentioned above. The two flaps thus hang from opposite edges of the top of the bag, one hanging free, and the other folded over the first, and serving to close the bag. The plastics material outside the inverted U-cut forms the shoulder strap.

BRIEF DESCRIPTION OF THE DRAWINGS

FIG. 1 is a perspective view of a shoulder strap bag in accordance with the invention;

FIG. 2 is an elevational view taken in the direction of the arrow 2 in FIG. 1;

FIG. 3 is a side elevational view of the bag, with the flaps in "up" position, as they were at the time of initial cutting; and

FIG. 4 is a transverse section taken on line 4—4 of FIG. 3.

DESCRIPTION OF A PRESENT ILLUSTRATIVE EMBODIMENT

In the drawings, a shoulder strap bag in accordance with the invention is shown generally at 10, the bag part at 11, the shoulder strap at 12, and the pocket flaps at 13, there being two flaps 13 in this instance of identical shape and construction, hanging one in front of the other, as seen best in FIGS. 1 and 2. The bag part comprises two opposed side panels 11a, with a horizontal top edge and flap fold line at 11b.

In FIG. 3, as well as in FIG. 4, it can be seen that the article is fabricated from a thin, flexible tube of plastics material, designated at 15 in FIG. 4. In the making of the article, this tube is flattened as seen in FIG. 4, where the bag may be considered as lying flat on a flat surface, not shown. At the time of cutting the material, done preferably with a die cutter, and with the article in the flattened position of FIG. 3, the two sides 15a and 15b of the tube may be regarded as resting one on the other, with the two resting on the support surface. The bag is formed at the bottom with a weld seam, which can be either a seal made by heat or it can be a sonic seal. Thus, the bag has a sealed bottom end 16.

15 The construction of the bag is as follows:

Certain dimensions were given for a typical bag in accordance with the invention in the introductory portion of the specification, and while typical, it will of course be understood that such dimensions are not limitative

20 on the invention. Accordingly, a thin, flexible plastic tube, of suitable dimensions, is provided. With this tube thus flattened and resting on a support surface, as mentioned hereinabove, an inverted U-shaped cut 18 is then made, using preferably, though not necessarily, a cutting die. For a bag of dimensions heretofore mentioned, this cut 18 begins at a point 19 spaced inwardly from one side edge of the bag by approximately 1 $\frac{1}{4}$ inches, and spaced above the bottom of the bag by about 12 inches. The cut 18 extends vertically from this point 19, up and then around the curved upward corner portion 20 of the bag at uniform spacing from the outer margin thereof, thence horizontally across the bag at the same spacing, inside and around the other rounded corner of the bag, still at the same spacing, and thence vertically downward to a point 22 which is located similarly to point 19 but on the opposite edge portion of the bag.

The beginning tube, above the bag, is thus formed or divided into a shoulder strap, and two flaps or aprons 40 13, one of which is folded outwardly and down, and the other of which is folded over the open upper end side of the bag, and thence dropped downwardly on the outside of the first mentioned flap or apron, to the position clearly shown in FIG. 2. Vertical cuts such as 24 may be made in the free ends of the flaps 13, and hang as decorative fringe when the bag is in the position of FIGS. 1 or 2.

In use, the strap 12 is slung over the shoulder, flaps 13 on the outside. To gain access to the bag, the outer flap 13 is simply lifted.

It will be seen that the bag as thus made can be manufactured at a very low cost, sufficiently low that the article can be treated as a give-away item, in which case, of course, the flaps, or the outer flap, may bear advertising words or indicia. The bag is very convenient in use, and affords an excellent bag into which a dress, for example, properly folded, can be packaged. The article is thus suited to a merchandising program in which the carrying bag of the invention can be supplied to the customer to carry away a purchased item such as a dress.

The invention is of course capable of being embodied in various dimensions, various materials, and for various specific uses, and it is also possible to make many changes in the form or structure of the bag without departing from the spirit and scope of the invention as defined in the appended claims.

I claim:

1. A shoulder strap bag composed of a flexible material, comprising:
  - a tube of said material having a seam closing a lower end thereof, and providing two opposed side panels which are adapted to lie substantially flat in a plane containing said seam, 5
  - at least one of said side panels terminating at an uppermost horizontal edge,
  - a flap integrally joined to said uppermost horizontal edge and adapted to be folded over the other side panel to close the bag, and
  - opposite vertical and edge portions of said tube having vertical extensions rising above said side panels at opposite ends thereof and extended inwardly 10 towards and joined to one another at the top to

form a shoulder strap, said extensions forming said shoulder strap comprise two overlying vertical strips at each said opposite ends, said overlying vertical strips being integral with the material of the bag and integrally joined together along the outer vertical edges thereof to points near the top of the shoulder straps, a pair of generally horizontal top strips unjoined to each other and adapted to lie adjacent to one another, said top strips being integrally joined to said overlying vertical strips at the ends thereof and forming said shoulder straps.

2. The subject matter of claim 1, wherein each of said side panels is furnished with an integrally joined flap, and one hangs from the upper edge of its side panel, and the other folds thereover.
